(57) **CLAIM**

We claim the ornamental design for a toy wagon, as shown and described.

DESCRIPTION

FIG. 1 is a front perspective view of the toy wagon;

FIG. 2 is a top plan view thereof;

FIG. 3 is a bottom plan view thereof;

FIG. 4 is a front elevational view thereof;

FIG. 5 is a rear elevational view thereof; and,

FIG. 6 is a right side elevational view thereof, the left side elevational view being a mirror copy of this view.

The dash lines included are for illustrative purposes only and are not part of the claimed design. The shading illustrated in the figures is provided merely to represent the contour of the design and is not intended to be illustrative of texture, gloss, or surface decoration.
